UNITED STATES PATENT OFFICE.

WILLIAM F. STAGGERS, OF MANNINGTON, WEST VIRGINIA.

WINDOW-SASH FASTENER FOR LOCKING WINDOWS IN PARTIALLY-OPEN POSITION.

1,407,006.

Specification of Letters Patent. Patented Feb. 21, 1922.

Application filed March 12, 1921. Serial No. 451,673.

To all whom it may concern:

Be it known that I, WILLIAM F. STAGGERS, a citizen of the United States, residing at Mannington, in the county of Marion and State of West Virginia, have invented a new and useful Window-Sash Fastener for Locking Windows in Partially-Open Position, of which the following is a specification.

The object of my invention is to provide a simple locking device adapted to lock the upper and lower sashes to each other, when either or both are partly open, in combination with a gravity controlled fastener that will admit of lowering but prevent raising of the lower sash when the upper and lower sash are unlatched from each other.

It is further an object of my device to provide a device of this nature that can be manufactured at small cost and can be readily applied to the window sash at small expense. I attain these and other objects of my invention by the mechanism illustrated in the accompanying drawings, in which—

Figure 1 is a front elevation of a window with my device applied thereto;

Fig. 2 is a horizontal section approximately on the line 2—2 of Fig. 1;

Fig. 3 is a detail perspective view of my device removed from the sash;

Fig. 4 is a similar perspective view of a slightly modified form of the invention;

Fig. 5 is a perspective view of a modified form of the device in which spring 8 is omitted, member 6^a being itself of spring metal thus making the spring 8 unnecessary; and

Fig. 6 is a detail perspective of plate 3.

Like characters of reference designate like parts in each of the several views.

Referring to Figs. 1 and 2 of the accompanying drawings, the upper sash 1 is provided with vertically extending plates 3 having suitable spaced openings 4 of suitable size to receive the locking projection 7 of the spring controlled sash fastener. Referring to Figs. 2, 3, and 4, I provide a plate 5 of sheet metal having a plurality of suitable openings 20 for any suitable screws to fasten the plate to the top horizontal strip of the

lower sash of the window. Horizontally attached to the plate 5 is a pivoted latch 6 having a locking projection at latch end 7 of suitable size to releasably engage in any of the openings 4 in the plate 3 which plate 3 is fastened to the vertical strips of the upper window sash 1. I provide a suitable spring

8 resiliently pressing member 6 toward member 3. Attached to the outer portion of pivoted latch 6 I provide a socket 11 in which is mounted a bail 10, which carries a roller 9, said bail being of sufficient length so that the roller 9 may swing past the latch end or projection 7 to either an operative or inoperative position. The roller 9 is of sufficiently large diameter to project beyond the member 7 and hold said member disengaged from the perforated strips 3 when the roller 9 is in operative position shown in Fig. 3. Pivoted latch 6, which is preferably formed from a metal plate, is provided with cut-out portions 12 for the bail 10. Also horizontally mounted on plate 5 at right angles to the pivoted latch 6, I provide a gravity locking member 13, preferably formed of sheet metal as illustrated, and provided with a suitable clamp or wedge member, which in turn is provided with a suitable flexible or resilient pad 15 adapted to abut against the window frame in proximity to the upper horizontal strip of the lower window sash, whereby to block said sash against being raised, while permitting of its being lowered at will, without touching the gravity fastener 13.

Referring to Fig. 4 I may provide the gravity locking element 13 with a suitable threaded or unthreaded socket 17, adapted to receive a pin 13 which carries a suitably rounded resilient buffer element adapted to engage the side frame of the window, operating in substantially the same manner as the members 14 and 15. It is within the contemplation of my invention to provide either one fastener for one side of the window or two of them on opposite sides as shown in Fig. 1.

Referring to Fig. 5 there is a modification of my invention having a plate 6^a formed integrally with plate 5, to permit of stamping of both members out of a single strip of metal, the member 6^a being sufficiently resilient to permit of its operation in substantially the same manner as the member 6, but without requiring the use of the spring 8 or the horizontal construction illustrated in the other figures. In operation the device shown in Fig. 5 is used in the same manner as the device shown in Figs. 3 and 4.

What I claim is—

1. In a window sash fastener, the combination of a plate affixed to the top of the horizontal strip of the lower sash, a spring

controlled latch hingedly mounted on said plate, a vertical plate attached to the upper sash with which said latch may be releasably engaged at any of a series of perforations in 5 said strip, a roller exceeding in diameter the projection on the pivoted latch member, and a bail mounted on said latch member and carrying said roller, said bail being suitably positioned and of sufficient length to permit 10 of swinging the roller past the locking projection of the pivoted latch element.

2. In a window sash fastener, the combination of a plate affixed to the top of the horizontal strip of the lower sash, a spring 15 controlled latch hingedly mounted on said plate, a vertical plate attached to the upper sash with which said latch may be releasably engaged at any of a series of perforations in said strip, a gravity locking member hingedly mounted on the plate which is affixed to the horizontal strip of the lower sash, said gravity locking member having a buffing element mounted on its free end adapted to frictionally engage the frame of the window 20 to prevent raising of the lower sash by any one from the outside while permitting of the lowering of the sash without touching the locking element.

3. In a window sash fastener, the combination of a plate affixed to the top of the horizontal strip of the lower sash, a spring 30 controlled latch hingedly mounted on said plate, a vertical plate attached to the upper sash with which said latch may be releasably engaged at any of a series of perforations in 35 said strip, a roller exceeding in diameter the projection on the pivoted latch member, a bail mounted on said latch member and carrying said roller, said bail being suitably positioned and of sufficient length to permit 40 of swinging the roller past the locking projection of the pivoted latch element, a gravity locking member hingedly mounted on the plate which is affixed to the horizontal 45 strip of the lower sash, said gravity locking member having a buffing element mounted on its free end adapted to frictionally engage the frame of the window to prevent

raising of the lower sash by anyone from the outside, while permitting of lowering of 50 the sash without touching the locking element.

4. In a device for locking sashes of windows together when one or both of said windows are partially open, the combination 55 of means on one of the windows for receiving the latch end of a locking element, a base plate attached to the other window sash, a spring controlled latch hingedly mounted on said base plate and adapted to releasably engage at any of a series of spaced positions with the other sash when either is raised or lowered, and gravity operated hinged locking means, said means having a buffer member on the end thereof frictionally engaging 60 the frame of the window to prevent raising of the lower sash.

5. In combination with the apparatus described in claim 5, a roller element swingably attached to the spring controlled latch element, said roller being of sufficient diameter to hold the latch end disengaged from the other sash when said roller is in operative position, and means for shifting said roller into and out of operative position 75 at will.

6. In a window sash fastener of the class described, the combination of perforated lock engaging means attached to the vertical sash of the upper window, and a locking device detachably engageable therewith, said device consisting of a plate secured to the top of the upper horizontal portion of the lower sash, an upright locking element 80 resiliently pressed toward and normally engaging the lock means on the upper window sash, and a second locking device hinged to the aforesaid plate, a buffer member on said second locking device, said buffer member engaging by gravity frictionally 85 with the side of the window frame immediately above the lower sash when said second locking device is disposed in its normal diagonal position, substantially as described and shown.

WILLIAM F. STAGGERS.
